AIRPLANE

Edward M. Davis, Northridge, and William M. Hannan,
North Hollywood, Calif., assignors to Lockheed Aircraft Corporation, Burbank, Calif.

Filed Sept. 11, 1967, Ser. No. 8,558

Term of patent 14 years

(Cl. D71—1)

FIG. 1

Fig. 2

FIGURE 1 is a perspective view of the airplane, showing our new design;

The dominant features of our design reside in the portions shown in full lines.

We claim:

The ornamental design for an airplane, as shown and described.
